US0D1073018S

(12) **United States Design Patent** (10) Patent No.: **US D1,073,018 S**
(45) Date of Patent: ** Apr. 29, 2025

(54) **PRESSURE REDUCER**

- (71) Applicant: **STEGO HOLDING GMBH**,
Schwaebisch Hall (DE)
- (72) Inventors: **Bernd Armin Schanzenbach**,
Mainhardt Geisselhardt (DE); **Susanne
Luz**, Waiblingen (DE)
- (73) Assignee: **STEGO HOLDING GMBH**,
Schwaebisch Hall (DE)

(**) Term: **15 Years**

(21) Appl. No.: **35/514,845**

(22) Filed: **Feb. 1, 2022**

(80) **Hague Agreement Data**

Int. Filing Date: **Feb. 1, 2022**
Int. Reg. No.: **DM/219804**
Int. Reg. Date: **Feb. 1, 2022**
Int. Reg. Pub. Date: **Aug. 5, 2022**

(30) **Foreign Application Priority Data**

(57) **CLAIM**

The ornamental design for a pressure reducer as shown and described.

DESCRIPTION

1.1 is a front elevation view of a pressure reducer in accordance with the new design;

1.2 is a back elevation view thereof;

1.3 is an exploded perspective view thereof; and

1.4 is a side elevation view thereof.

The broken lines depict portions of the pressure reducer that form no part of the claimed design.

1 Claim, 4 Drawing Sheets
